UNITED STATES PATENT OFFICE.

WILLIAM D. MURPHY, JR., OF CHICAGO, ILLINOIS.

DESIGN FOR A LAMP-SUPPORT.

SPECIFICATION forming part of Design No. 35,142, dated October 1, 1901.

Application filed April 24, 1901. Serial No. 57,331. Term of patent 3½ years.

To all whom it may concern:

Be it known that I, WILLIAM D. MURPHY, Jr., a citizen of the United States, residing at Chicago, in the county of Cook and State of Illinois, have invented and produced a new and original Design for Lamp-Supports, of which the following is a full, clear, concise, and exact description, reference being had to the accompanying drawings, forming a part 10 of this specification.

My invention relates to a new and original design for a lamp-support, as shown in the accompanying drawings, in which—

In said drawings the upper part of the support consists of the globe or reservoir a , from which depends the vertical pipe or rod a^2 , having a distinct bend at a^3 and formed into a circular hook a^4 , the end a^5 of said hook and 20 the bent portion thereof adjacent the vertical rod or pipe being at an angle to said vertical part.

I claim—

The design for a lamp-support substantially 25 as shown and described.

In witness whereof I have hereunto subscribed my name in the presence of two witnesses.

WILLIAM D. MURPHY, JR.
